UNITED STATES PATENT OFFICE.

THOMAS A. PORTER, OF CAMERON, TEXAS.

WATER-ELEVATOR.

SPECIFICATION forming part of Letters Patent No. 329,485, dated November 3, 1885.

Application filed July 30, 1884. Serial No. 139,144. (No model.)

To all whom it may concern:

Be it known that I, THOMAS A. PORTER, of Cameron, in the county of Milam and State of Texas, have invented a new and useful Improvement in Water-Elevators, of which the following is a full, clear, and exact description.

This invention relates to an endless-chain water elevator; and the invention consists of the construction, arrangement, and combination of parts, all as hereinafter described, and specifically pointed out in the claim.

Reference is to be had to the accompanying drawings, forming part of this specification, in which similar letters of reference indicate corresponding parts in all the figures.

Figure 1 shows in sectional elevation my new elevator arranged in a well. Fig. 2 is a front elevation of the elevator, the well and curb being shown in section. Fig. 3 is a sectional plan view taken on the line $x-x$ of Fig. 1. Fig. 4 is a similar view, showing a modified form of bucket, and Fig. 5 is a front elevation of the modified form of bucket.

A A represent two endless chains. B B' represent the drums over which the endless chains pass, and C C represent the buckets, made, preferably, cylindrical in form, and formed or provided with the side flanges c c, by which the buckets are secured to and between the endless chains A A. The drum B is made fast upon the crank-shaft D, which is journaled at the upper edges of the curb-boards E E, and the said drum is circumferentially grooved in the center, as shown clearly in Fig. 2, to form the side flanges b b, and to form a clearance for the passage of the buckets C around the drum. The flanges b b are made many-sided—in this instance six-sided—and in the center of every other flat side of the flanges is formed a projection or toe, b', which are adapted to pass through the slots a' of the link-plates a of the chains A, to cause the chains to travel together, and to prevent them from slipping off from the flanges b of the drum B when it is revolved by power applied to the crank-shaft D. The endless chains A A are made up of the short and narrow metal plates a a' a'', which are linked together, as shown at a''. The links a 50 have the above-mentioned slots a' made

through them to engage with the toes b'. The links a' are plain links, while the links a'' have the staples d formed upon their outer surfaces, which are adapted to pass through the slots d', made in the side flanges, c c, of the buckets C, and to receive the key-rings e e for securing the buckets to the chains A, as will be clearly understood from Fig. 2.

To one end of the curb-boards E E is secured the receiver F, into which the buckets 60 C successively empty their contents, and from the bottom of the receiver F leads the pipe F', which serves to conduct the water away from the receiver F to any point desired; and in order that the buckets C shall pour their entire contents into the receiver F without permitting any water to fall back into the well, I form the buckets with the spouts C', and attach them to the chains A A at points at or near the center of the length of the buckets, 70 so that the open ends of the buckets, in passing over the drum B, will not tip forward until the spouts are carried just above the inner wall of the receiver.

Instead of forming the buckets with side 75 flanges, as shown in Figs. 1, 2, and 3, the buckets may be secured to plates or cross-pieces, as shown in Fig. 4, in which case the drums B B' need not be circumferentially grooved, as shown in Fig. 2, and instead of making the 80 buckets cylindrical they may be made square in cross-section, as shown in Fig. 4, or they may be made in any desired form.

Constructed as described, the elevator is very rapid in its action, and it is strong, cheap, 85 and durable.

Having thus described my invention, what I claim as new, and desire to secure by Letters Patent, is—

The combination, with endless chains having the links a'', provided with staples d, of the buckets C, having apertured side flanges through which the staples pass, and fastenings e, passing through the staple in front of the apertured side flanges to hold the buckets in 95 place, substantially as set forth.

THOMAS A. PORTER.
